GARAGE JACK

Thomas J. McCarthy, York, Pa., assignor to The MacOjac Company, Newark, N. J., a corporation of New Jersey

Application June 12, 1934, Serial No. 730,310

9 Claims. (Cl. 254—6)

This invention relates to a lifting jack which is more particularly adapted for use in garages, repair shops and the like.

An object of the invention is the construction of a simple and efficient jack that can be manufactured at a relatively low cost.

Another object of the invention is the construction of a jack that is provided with novel means for lifting and lowering the saddle plate, keeping said plate at all times in a perfect horizontal position for efficient results.

A still further object of the invention is the construction of a wheeled garage jack that can be quickly positioned under a motor vehicle, and which also can be quickly operated for efficiently raising or lowering the vehicle.

With the foregoing and other objects in view, my invention comprises certain novel constructions, combinations and arrangements of parts as will be hereinafter fully described, illustrated in the accompanying drawings, and more particularly pointed out in the appended claims.

In the drawings:

Figure 1 is a vertical, central, longitudinal sectional view of a mechanism constructed in accordance with the present invention, while

Figure 2 is a top plan view of the same.

Figure 3 is a sectional view taken on line 3—3, Fig. 1, and looking in the direction of the arrows.

Figure 4 is a fragmentary perspective view of the mechanism, showing particularly the saddle and the saddle plate.

Figure 5 is a fragmentary, perspective view of the mechanism showing particularly the rear end and the bar device.

Figure 6 is a plan view of the bar device.

Referring to the drawings by numerals, 1 designates the frame as a whole; said frame is provided with two sides 2, Fig. 3. The frame 1 is provided with stub axles 3 on which are mounted master wheels 4. On the forward end of frame 1 are two swivelled wheels 5. A swivelled wheel 6 (Fig. 1) is located on the rear of the frame, preferably in the middle thereof.

A segmental worm gear 7 is journalled on the upper portion of the frame 1 at 8, and this gear has its worm teeth 9 meshing with worm 10 (Fig. 1). This worm 10 is suitably mounted on frame 1 and is connected by a universal joint device 11 with the handle or operating rod 12. The handle 12 can be of any desired length, for operating the jack with ease, irrespective as to the type of motor vehicle being operated upon, and to assist in the operation I preferably place

a cross bar 13 on the outer end of handle 12 with grips 14 thereon.

The universal joint device 11 comprises the ball-like end 15 of the worm 10 (Fig. 1) with outwardly extending lugs 16. These lugs 16 are engaged by the yoke-like member 17 formed on the inner end of the handle 12.

The worm gear 7 is provided with an upwardly extending short shoulder 7a, rounded on top as at 7b, Fig. 4. The saddle 18 is pivotally mounted at 19 on the upper end of shoulder 7a of the gear 7. This saddle 18 is provided with two sides 20 and with a flat top 21. Integral with top 21 is a round head 22. In this head 22 is an annular groove 23. A saddle plate 24 is mounted on head 22 and extends downwardly around said head. A set screw 25 (Fig. 1) extends through the lower part of the saddle plate 24 and into groove 23 detachably securing the plate in position. The saddle 18 is provided with an auxiliary saddle rest 26. This rest 26 may be used on which to rest an axle or a part of a motor vehicle, if the operator so desires.

Two short guiding links 27 are used, each having a bifurcated inner end 28. The outer ends of short links 27 are pivotally mounted, at 29, on the lower end of the saddle 18. The bifurcated ends 28 of said short links straddle the sides 2 of frame 1 and are pivotally mounted on said sides at 30.

A suitable housing or cover 31 (Fig. 1) is placed over part of the mechanism, against the upper portion of the frame 1.

The inner ends of sides 2 are provided with teeth 32. A bar device 33 is mounted on handle 2. This bar device comprises a hub 34 that surrounds the handle, with outwardly-extending arms 35 at opposite sides of the hub. Each arm 35 is provided on its inner face with an outwardly-extending tooth 26 that is adapted to engage the teeth on the ends of the frame. In apertures 37 of arms 25, I place the inner ends of coil spring 38 with the outer ends of said springs fastened over the pins 39 on the sides of the frame. These springs 38 hold the teeth of the bar device in engagement with the teeth on the frame, whereby the handle is held in an inclined adjusted position. Of course, the handle by this simple fastening device may also be retained in a horizontal position, as a wide range of adjustment can be obtained for the handle by my novel bar device locking means. The hub 34 can be slid outwardly on handle 12, to permit the handle to swing to the desired position. Then upon releasing the hub, springs 38 will

move the teeth of the bar device into contact with the teeth on the frame, thereby holding the handle adjusted. It is obvious that the universal joint device 11 permits free adjustment 5 of the handle 2, in a vertical plane.

After the jack is placed under the motor vehicle, with the saddle plate 24 in position for lifting the load, and the handle 2 has been adjusted to suit the individual operator, then upon 10 rotating the handle, the gear 7 will be revolved around its pivot 8, thereby raising or lowering the saddle 7 as the case may be, and during this raising or lowering of the saddle, the saddle plate 24 is always kept in a true horizontal position 15 by reason of the action of the short guiding links 27. The lift of the gear 7, on the saddle 18 is always directly under the saddle plate, giving a great power to the mechanism, with a minimum number of parts, as well as a minimum 20 length or size of the parts of the unit. In other words, I have produced a very compact and efficient mechanism for lifting or lowering a load.

The bifurcated structure 28 of the short links 25 assist in retaining the saddle 18 from moving too far downward, or into contact with the support or floor upon which the jack is resting. This is desirable because in my jack the gear 7 is of a very compact structure, and is ready to act immediately upon turning the handle to lift the load; the guiding links 27 also serving to hold the saddle in a perfect perpendicular plane, right over the pivot on the gear 7, thereby properly positioning the saddle plate at all times with the minimum number of parts and material employed, for accomplishing this efficient function 30 and operation, as disclosed in my novel mechanism.

While I have described the preferred embodiment of my invention and illustrated the same in the accompanying drawings, certain minor changes or alterations may appear to one skilled in the art to which this invention relates, during the extensive manufacture of the same, and I, 45 therefore, reserve the right to make such changes or alterations as shall fairly fall within the scope of the appended claims.

What I claim is:

1. In a mechanism of the class described, the 50 combination of a frame, a worm gear movably mounted on said frame, a saddle provided with a saddle plate movably mounted on said worm gear, manually operated means including a handle for operating said worm gear, and a locking device slidably mounted on the handle and engaging means on said frame for locking the handle in different positions.

2. In a mechanism of the class described, the 60 combination of a frame, a worm gear movably mounted on said frame, a saddle provided with a saddle plate movably mounted on said worm gear, manually operated means including a handle for operating said worm gear, and locking means on said handle and frame for locking the handle in different adjusted positions.

3. In a mechanism of the class described, the 65 combination of a frame, a worm gear movably mounted on said frame, a saddle-plate-carrying saddle movably mounted on said worm gear, manually operated means including a handle for 70

operating said worm gear, and locking means on said handle and frame for holding said handle in an adjusted position.

4. In a mechanism of the class described, the 5 combination of a frame, a worm gear movably mounted on said frame, a saddle-plate-carrying saddle mounted on said worm gear, manually operated means including an adjustable handle for operating said worm gear, and means co-operating with said adjustable handle and a portion of said frame for permitting adjustment 10 of the handle and the retention of the handle in different adjusted positions.

5. In a mechanism of the class described, the 15 combination of a frame, a worm gear pivotally mounted on said frame, a saddle provided with a saddle plate pivotally mounted on said worm gear, manually operated means including a handle on said frame for operating said worm gear, and adjustable locking means on said handle and frame for holding the handle in adjusted 20 positions.

6. In a mechanism of the class described, the 25 combination of a frame, a worm gear pivotally mounted on said frame, a saddle provided with a saddle plate pivotally mounted on said worm gear, manually operated means including a handle on said frame for operating said worm gear, teeth formed on said frame, and a sliding bar device on said handle and provided with 30 teeth for engaging the teeth of the frame for holding the handle in an adjusted position.

7. In a mechanism of the class described, the 35 combination of a frame, a worm gear pivotally mounted on said frame, a saddle provided with a saddle plate pivotally mounted on said worm gear, said frame provided with sides, said sides provided around their inner ends with rows of teeth, manually operated means including a handle on said frame for operating said worm 40 gear, a bar device comprising a hub around said handle and with oppositely extending arms over the toothed ends of said sides, each arm provided on its inner face with a tooth registering with all of the teeth on the inner end of one of the sides, said sides provided with outwardly-extending pins, and coil springs fastened at their outer ends to the outer ends of said arms and at their inner ends to said pins, substantially as shown and described.

8. In a mechanism of the class described, the 50 combination of a frame, a worm gear pivotally mounted on said frame, a saddle provided with a saddle plate pivotally mounted on said worm gear, manually operated means including a universal 55 joint device and handle for operating said worm gear, and a locking device on said handle and frame for holding said handle in adjusted positions.

9. In a mechanism of the class described, the 60 combination of a frame, a worm gear pivotally mounted on said frame, a saddle provided with a saddle plate pivotally mounted on said worm gear, manually operated means including a universal 65 joint device and handle for operating said worm gear, and a locking device slidably mounted on the handle and engaging means on said frame for locking the handle in different vertical positions.
